I. STERN

REMOVABLE BRIDGEWORK ATTACHMENT

Filed Dec. 3, 1920.

Inventor
Isidore Stern
By
James C. Ledbetter
Attorney

UNITED STATES PATENT OFFICE.

ISIDORE STERN, OF NEW YORK, N. Y.

REMOVABLE BRIDGEWORK ATTACHMENT.

Application filed December 3, 1920. Serial No. 427,936.

To all whom it may concern:

Be it known that I, ISIDORE STERN, a citizen of the United States, residing at New York, borough of Manhattan, in the county 5 of New York and State of New York, have invented certain new and useful Improvements in Removable Bridgework Attachments, of which the following is a specification.

10 This invention relates to dentistry and especially to removable bridge-work; and more particularly it relates to adjustable removable bridge-work attachments.

15 An object of this invention is to produce a novel and improved removable bridge-work attachment which may be adjusted to take up wear, occasioned thru continued use with removal and replacement, so that the bridge will remain in firm position in one's 20 mouth.

It is likewise an object to produce an attachment for removable denture which may be adjusted through the agency of a suitable pressing or adjusting tool so the attachment 25 may be adjusted by the wearer to refit the bridge attachment into the mouth so that all looseness and play is eliminated.

In producing the bridge-work attachment as embodied in this invention, I have in 30 mind the attachment design disclosed in my copending application for patent filed November 8, 1920, and identified under Serial Number 422,653 in the United States Patent Office; and it is an object to produce an attachment of similar character and advantages but somewhat distinguished in construction.

The advantages of removable bridge-work lie in the fact that the bridge may be so 40 constructed and placed in the mouth that adequate relative movement may take place between the bridge-work attachment itself and the sound teeth, pier or abutment teeth acting as points of support, that the disadvantages of immovable and fixed bridge-work is overcome; and furthermore the bridge may be removed to be cleaned which maintains the parts in more sanitary condition than heretofore possible with the old-style fixed bridge permanently mounted in 45 the mouth.

Referring to the accompanying drawings forming a part hereof, Figure 1 shows a plan view of a dental bridge with my improved attachments anchored thereto, with

an adjusting tool placed in position over one of the attachments and made ready for the adjusting operation.

Figure 2 shows three projections of the attachment namely, a front, side, and bottom view.

Figure 3 shows a perspective view of the attachment in position ready to slide into a tubular socket forming part of the dental device.

Figure 4 shows a plan view of a bridge, or artificial tooth as sometimes called, with the improved attachments soldered, welded or otherwise made an integral part thereof; and in this view the attachments have been 70 acted on by an adjusting tool to the extent that they are slightly bent or distorted in order to effect a close and tight fit into the tubular socket.

Referring further to the drawings for a 75 more detailed description of the invention, there is shown a metal device having a general T-shaped cross section form; and this device or attachment comprises a shank 6 projecting from a web 7 having parallel 80 bead-edges or cylindrical edges 8. The shank 6 is made longer or broader than actually used, but is cut down when soldered to a bridge. The bead-edges are made cylindrical or round and slightly larger or 85 greater in diameter than the thickness of the web 7; but I do not limit myself to this particular design for indeed the attachment may be practically built and used by omitting the bead-edges and rounding off the 90 edges of the web or leaving them finished square or flat. However there is an inherent advantage in the cylindrical bead-edges as later explained.

A bridge 9 is built up of either porcelain 95 or gold, as known to those conversant with the art, and has two attachments anchored thereto as shown. This bridge is removably mounted in the mouth and held by the attachments disposed in the sockets as is usual 100 with bridge-work of the removable class.

A socket 10 is made the counter-part of the attachment, and has the tubular sockets 11 to receive the bead-edges 8 of the attachment. The socket is made open down one 105 wall thereof, as designated by 12, to receive the shank. This socket is usually embedded in an inlay which in turn is anchored to sound teeth acting as points of support. The manner of preparing the points of sup- 110

port and fitting in the sockets is known to those skilled in the art and is therefore not set forth in detail herein.

It is understood from the foregoing description just how the attachment registers with and tightly fits into the socket 10; and it is a known fact with users of this class of device that constant removal and replacement of the bridge-work will wear the attachment parts to such an extent that looseness becomes apparent and thereafter the bridge is somewhat unsatisfactory. To overcome this trouble of looseness is one of the objects of my invention, and accordingly my attachment is so constructed that it may be reformed or distorted in shape, by a suitable pressing or adjusting tool, so that it may be adjusted from time to time and thus made to more firmly fit into the socket to avoid undue looseness or the possibility of falling out of one's mouth.

One suitable form adjusting tool comprises a handle 15 joined to a body portion 14, and the body is made with hooks 16 which leaves an opening thru the body similar in size and shape to the attachment. The tool may therefore be placed upon the attachment as shown in Figure 1 with the hooks 16 reaching around the cylindrical 30 bead-edges 8. A screw 17 forms part of the tool and is adapted to press and clamp against the web 7 centrally between the edges thereof. The screw is provided with a knurled thumb-piece or hand-wheel 18 so that the clamp screw 17 may be forcibly driven against the attachment for the purposes herein described.

In the use of the tool 15 in connection with the dental attachment, the tool is 40 placed over the attachment with the hooks 16 engaging the bead-edges. The screw is then turned until considerable pressure is exerted against the web 7 whereby the hooks 16 draw outwardly on the bead-edges to slightly distort and bend the web, leaving it in a reformed and curved shape as shown in Figure 4. Considerable curvature is imparted to the webs 7 of the two attachments constituting a part of the bridge 9 50 as shown in Figure 4. This curvature is given the attachments by proper use of the tool 15. The bridge after slight reformation of the attachments 7 is ready for replacement in the mouth; and the attachments now fit very tightly into the socket 10 by virtue of the distorted shape imparted to the bridge parts 7.

An important result attained by the use 60 of this dental bridge attachment is the avoidance of what is usually known as "point contact" of the two fitting parts. In the case of a dental bridge-work attachment not having the round or cylindrical bead-edges 8, it would be practically impossible to distort the web 7 without leaving a point

contact only between the attachment and the tubular socket part; and this is true because the distorted web 7 when inserted in the tube would touch the socket only in points. In the present design where the 70 web 7 is finished on the edges thereof with a cylindrical formation, this difficulty does not exist because the cylindrical wall of the bead-edge will frictionally engage more tightly the interior wall of the socket, thereby avoiding point contact. In other words, the distortion of the web 7 slightly displaces the cylindrical edges 8 which causes said edges to take up a new and closer position relatively with the tubular parts 11 of 80 the socket, and though I have shown one preferred form of construction, I do not limit myself thereto, but claim a right of protection as to obvious changes which come within the scope of my invention. 85

This form of dental attachment for use in connection with removable bridge-work overcomes the disadvantages of looseness and poor fitting of parts so common in that 90 class of dentistry.

Having described the construction and use of the devices constituting my invention what I desire to claim and secure by Letters Patent is—

1. A removable bridge work attachment comprising a T-shaped device having opposed edges, said opposed edges being round in form to approximate the shape of a cylindrical body.

2. A removable bridge work attachment 100 constructed in the form of a T, and parallel cylinders integrally formed on the attachment.

3. A removable bridge-work attachment and socket therefor, comprising a shank by 105 which the attachment is anchored to a bridge, a web made on the shank, cylindrical bead-edges formed on the web, and a socket made the counterpart of the attachment to receive said attachment.

4. A denture attachment for removable bridgework of the class employing a socket made in pier teeth to support the bridge, comprising a rectangular web, and a plurality of cylinder-like bead edges formed on the web, said attachment adapted to have 115 said edges adjusted to produce a snug fit between the attachment and socket, and a shank made on the web by which the attachment is anchored to a bridge.

5. A denture attachment to fit into a pier tooth socket, comprising a web having parallel edges, a cylinder-like bead edge made on each parallel edge, and a shank integrally formed with the web.

6. A denture attachment to fit into a 125 socket, comprising a pair of cylinders, a web interposed between and integrally formed with the cylinders, and a socket member comprising a straight sided receptacle to re- 130

ceive the web and round tubular receptacles to receive the cylinder.

7. A dental bridge attachment for removable dentures, comprising a socket member which has tubular receptacles, a shank by which the attachment is anchored to a bridge, a web attached to the shank and adapted to fit into the socket member, cylindrical edge formations made on the web and being adapted to fit into the tubular receptacles of the socket, the said web so constructed and having such adaptations as to provide for slight distortion in the shape thereof so that the cylindrical edges will more tightly fit and grip the tubular socket receptacles to take up for wear of parts and provide a denture of increased utility.

8. A dental bridge attachment for removable dentures, comprising a socket member having parallel tubular receptacles, a shank by which the attachment is anchored to a bridge, a web attached to the shank and adapted to fit into the socket, and rounded

cylinder-like edges made in parallel relation on the web and adapted to fit into the tubular receptacles, the attachment adapted to have the web thereof slightly distorted and curved by a suitable adjusting or pressing tool so that the web and cylinder-like edges are made to take up for wear and more snugly fit into the socket.

9. A dental bridge attachment for removable dentures comprising a socket having tubular receptacles, a shank by which the attachment is anchored to a bridge, a web made on the shank to fit into the socket, cylindrically formed edges made on the web to fit into the receptacles of the socket, and the said web being capable of slight curved reformation to compensate for wear whereby the web and edges thereof take up a new surface contact position within the socket.

In testimony whereof I hereunto affix my hand this 29th day of November, 1920.

ISIDORE STERN.
